LAPPING THREAD RING GAUGE

Alvin E. Langmaid, Bloomfield, and
Robert A. Bloom, Hartford, Conn.

Application September 23, 1948, Serial No. 50,812

9 Claims. (Cl. 51—32)

1

This invention relates to ring gauges of the type employed for testing threads of screws to determine their accuracy to the degree of perfection demanded by modern refinements of interchangeability.

The primary object is to provide means whereby thread forms may be produced in certain gauge parts of extremely hard material by lapping operations only.

With this and other objects in view which will become apparent in the following disclosure, the invention consists of mechanism including a novel form and arrangement of parts which are fully explained in said disclosure and illustrated in the accompanying drawings while the scope of the invention is defined by the appended claims.

In the drawings,

Figure 1 is a view of a ring gauge constructed in accordance with the invention.

Figure 2 is a sectional view on line 2—2 of Fig. 1.

Figure 3 is a longitudinal sectional view of a holder and associated parts employed for a lapping operation.

Figure 4 is a left end view of the assembly shown in Fig. 3.

Figure 5 is a view similar to Fig. 4 but with a cover plate removed.

Figure 6 is an enlarged detail view of certain assembled parts shown in Fig. 5.

Figure 7 is a sectional view on line 7—7 of Fig. 3.

Figure 8 is a detail view showing a method of assembling finished parts to form a thread ring gauge, and

Figures 9, 10 and 11 are detail views hereinafter more fully explained.

Referring to the drawings, the thread ring gauge illustrated in Fig. 1 comprises a body member 1, centrally bored at 2 to receive a plurality of suitably threaded circular ring sectors 3. These ring sectors, in blank form (see Figs. 9 and 10), are obtained with accurate and substantially identical contours by cutting a hollow cylinder (Fig. 9) into three equal parts with beveled or relieved corners as at 4 adjacent their inner peripheral surface which subsequently is helically grooved to form threads by a lapping operation. Each ring sector 3 is located within the body member 1, as in Figs. 1 and 2, with its outer segmental peripheral surface 5 in contact with the matching peripheral wall of bore 2 except at intermediate intervals where the wall of bore 2 is relieved to provide space areas 6 for reception

2

of a film of solder as 7 which is applied to secure each ring sector rigidly in its required position.

It will be apparent that body member 1 may be substantially like well known forms of ring gauges such for example as that established by American Gauge Design standards. Thus also provision for adjustability of gauge diameter if desired may consist of the conventional arrangement wherein the ring gauge or body member 1 is parted by a slot 8 extended from the periphery of the ring to the central bore 2, while similarly, slots as 9 and 10 may be extended from the bore but terminated at suitably placed stop holes, 11 and 12 respectively. This arrangement serves to impart and distribute resiliency throughout the body of the ring member so as to permit flexing thereof as may be effected by screw adjusting means 13 housed in bore 14 which extends through the body member in intersecting relation to slot 8, all in accordance with standard design well known in the art.

Means will now be described for holding ring sectors 3 precisely in required relation within body member 1 while the securing film of solder 7 is applied within the relief intervals 6. For this purpose a fixture employed may comprise a base 9' having secured therein an upright threaded plug 10' and also three upright pins 11'. A set screw 12' serves to secure in place whatever plug 25 as 10' may be appropriate to the particular thread form of a set of ring sectors which is to be assembled and secured in a body member 1. It will be apparent that the threads on a plug 10', by suitable engagement while in a common plane 30 with correspondingly formed threads on the ring sectors will locate the latter in their correct relative positions circumferentially of the body member. With the body member 1, ring sectors 3 and plug 10' assembled as indicated, pins 11' are each 35 adjusted and then secured as by respective set screws 15' with said pins in contact with body member 1 so that a three-point support is thereby provided which prevents accidental disarrangement of the several parts during the subsequent 40 application of solder to make the assembly permanent.

Means for producing thread forms on the circular ring sectors 3 by a lapping operation include a hollow holder 17, having at one end a nut receiving socket 18, with its outer end enlarged to form shoulder 19, and with a keyway provided at 20. At the opposite end, holder 17 is diametrically enlarged to provide for a chuck receiving socket 21. To reduce weight of holder 55 17 and to render parts therewithin visible and

accessible, the peripheral wall of the holder is cut away to form openings 22.

A nut 23 seated on shoulder 19 of socket 18, is keyed to the holder 17 at 24 and held therein against relative longitudinal movement by cap 25 which is screw threaded onto the holder. Engaged with nut 23 is a lead screw 26, terminating at one end in a shank 27 and provided at its opposite end with a socket 28 to receive split bushing 29 operable by screw 30 to clamp and rigidly secure in axial alignment with the lead screw 26 a lapping tool 31. For split bushing 29 there may be substituted others with bores of different diameter appropriate for the respective shanks of lapping tools of such diameter as may be required.

Within the socket 21 of holder 17 is seated chuck body 32 which is provided with recess 34 to receive blocks 35, preferably three in number, and of substantially triangular form, which are respectively secured to the chuck body in equally spaced relation as by screws 36 and dowel pins 37 to thereby form radially extending channels as 38. In each channel 38 is movably fitted a shoe 39, and between the shoe and peripheral wall 40 of the holder is placed a coiled spring 41, operable to yieldably urge the shoe toward a central axis which coincides with the central axis about which the lead screw and lapping tool with respect to the holder are adapted to be rotated. Each shoe 39 is provided with a peripheral wall 42 facing said central axis. This wall is provided with a relief notch 43 and on opposite sides thereof with beveled corners 44 which serve to limit peripheral wall 42 to desirable bearing areas for engagement with a ring sector 3. Inserted at the innermost apex of each block 35 is a respective stop pin 45. These pins serve a purpose that will presently become apparent. As a means to hold the several chuck elements described accurately seated within chuck body 32, there may be employed a cover plate 46, slotted as at 47 to receive screws 48 and with the slots enlarged as at 49 to provide for facility in removing the cover when the screws are slightly loosened. Serving to removably secure the chuck assembly described against longitudinal or rotative movement within its socket 21 of holder 17, set screw 50 and key pin 51 are interposed between the chuck body and holder. Thus the chuck assembly may be removed from the holder for use independently thereof and concerning which there will follow further explanation.

The shank 27 of lead screw 26 is adapted to be held in a chuck as 52, carried by a reversibly driven spindle (not shown). With the lead screw thus driven while holder 17 is held against rotation, the latter is caused to move back and forth longitudinally of the coincident axes of the lead screw and lapping tool, which of course are suitably threaded to correspond to a pitch of thread which it is desired to have formed in a set of circular ring sectors 3. Each one of a set of sectors is placed between a respective shoe 39 and the lapping tool 31 (see Fig. 6). The sectors while in this arrangement are each urged against the lapping tool by their respective spring backed shoe. After a comparatively brief period of the action indicated and just described, a helical groove is formed in the ring sectors 3 by abrasive effect of the threaded lapping tool. When this groove is formed to a slight depth it is sufficient to establish relative longitudinal movement between, the ring sectors and the chuck assembly as a whole, and the lapping tool, without assist-

ance of the leading effect initially required and imparted by the lead screw. In other words the chuck assembly together with the slightly grooved ring sectors held therein, may be removed from the holder 17 and transferred to an automatic machine for continued application of the lapping operation which may proceed with a successive use of lapping tools of respective suitably different diameters to compensate for wear on each tool prior to the final one used. The contour of each successive tool used may also be different as may be required to produce the finally desired profile, such for example as that shown in Fig. 6. As the effect of abrasive action of the lapping tools upon the ring sectors progresses during relative rotary and longitudinal movement therebetween, the sectors are advanced by the spring urged shoes until they engage respective stop pins 45. The location of these stop pins is such that when a ring sector has moved into position to engage them said sector is then substantially concentric to the axis of the threaded lapping tool, which signifies that thread formation on the sector is completed to within a few thousandths of an inch of the required depth. Thus when each sector of a set being lapped has been arrested by engagement with stop pins 45, it is thereby indicated that the lapping operation is substantially completed and the ring sectors are in readiness for assembly with a body member in accordance with the method of assembly as above explained. Subsequently slight further lapping is applied to the sectors in the permanently assembled gauge to impart thereto the exact dimensions required.

Thread forms shown in profile in several of the views of the drawings, are for convenience of illustrating, somewhat conventionalized, but a form of ring gauge thread employed for testing screw threads of American National form is shown in enlarged profile in Fig. 11 where it is indicated together with maximum diameter clearance space as at 53, this particular form being widely accepted practice in the manufacture of thread ring gauges.

It will be appreciated by those skilled in the art of gauge manufacture that the improved apparatus offered by our invention eliminates obstacles to accurate achievement encountered in the production of ring gauges made of material wherein the method employed may involve recourse to expedients such as annealing, tempering, sintering or grinding to create thread forms within bores of relatively small diameter.

Having thus described our invention what we claim is:

1. Mechanism for producing simultaneously by a lapping tool, thread forms upon a plurality of circular ring sectors which are adapted when so threaded to be mounted in a body member to form a thread ring gauge, said mechanism including in combination, a holder, a nut, a chuck, said nut and chuck being coaxially supported by the holder respectively at opposite ends thereof, a lead screw engaged by the nut, a threaded lapping tool rigid with the lead screw, extended longitudinally through the chuck and coaxial therewith, said chuck having channels therein radially extended from its central axis and including a follower shoe in each channel, each shoe being adapted to bear upon a circular ring sector interposed between said shoe and the threaded lapping tool, and means for yieldably urging each shoe toward the axis of the chuck to correspondingly press a respective circular

ring sector upon the threads of the lapping tool during relative reciprocatory and rotary movement between the lapping tool and holder.

2. Mechanism for producing simultaneously by a lapping tool, thread forms upon a plurality of circular ring sectors which are adapted when so threaded to be mounted in a body member to form a thread ring gauge, said mechanism including in combination, a holder, a nut, a chuck, said nut and chuck being coaxially supported by the holder respectively at opposite ends thereof, a lead screw engaged by the nut, a threaded lapping tool rigid with the lead screw, extended longitudinally through the chuck and coaxial therewith, said chuck having channels therein radially extended from its central axis and including a follower shoe in each channel, each shoe being adapted to bear upon a circular ring sector interposed between said shoe and the threaded lapping tool, means for yieldably urging each shoe toward the axis of the chuck to correspondingly press a respective circular ring sector upon the threads of the lapping tool during relative reciprocatory and rotary movement between the lapping tool and holder, and stop means for limiting movement of the circular ring sectors effected by movement of respective shoes.

3. Mechanism for producing simultaneously by a lapping process, thread forms upon a plurality of circular ring sectors which are adapted when so threaded to be mounted in a body member to form a thread ring gauge, said mechanism including in combination, a substantially cylindrical hollow holder having a nut receiving socket at one end and a chuck receiving socket at the opposite end, a nut, means for removably holding the nut in its socket in the holder, a chuck, means for removably holding the chuck in its socket in the holder, a lead screw engaged by the nut, a threaded lapping tool removably secured in rigid relation with the lead screw, extending longitudinally through the chuck and coaxially therewith, said chuck including a recessed body, blocks suitably arranged and secured in the recess of the chuck body thereby providing channels radially extended from the central axis of the chuck, and a follower shoe in each channel, each shoe being adapted to bear upon a circular ring sector interposed between said shoe and the threaded lapping tool, means for yieldably urging each shoe toward the axis of the chuck to correspondingly press a respective circular ring sector upon the threads of the lapping tool during relative reciprocatory and rotary movement between the lapping tool and holder, and stop means for limiting movement of the circular ring sectors effected by movement of respective shoes.

4. Mechanism for simultaneously producing by a lapping operation, thread forms upon a plurality of circular ring sectors with the threads formed on each section correlated to the threads formed on the other sectors whereby the several sectors when suitably secured in a body member form a thread ring gauge, said mechanism including in combination, a threaded lapping tool, a support for maintaining a plurality of circular ring sectors in coplanar relation around the lapping tool, means for yieldably urging the sectors to move toward the rotational axis of the lapping tool in respective radial paths while maintained in coplanar relation and normal to said axis, and stops extended from the support and adapted to engage adjacent end surfaces of respective sec-

tors to prevent radial movement of the sectors beyond a predetermined limit.

5. Mechanism for producing by a lapping operation, thread forms upon a plurality of circular ring sectors with the threads formed on each sector correlated to the threads formed on the other sectors whereby the several sectors when suitably secured in a body member form a thread ring gauge, said mechanism including a chuck, a threaded lapping tool extended longitudinally through the chuck and coaxial therewith, means for rotating and reciprocating the lapping tool relative to the chuck, said chuck having channels therein radially extended from the coincident axes of the lapping tool and chuck, a follower shoe confined in each channel for radial movement only, each shoe being engageable with a circular ring sector interposed between said shoe and the lapping tool, and means urging each shoe toward the lapping tool.

6. Mechanism for producing by a lapping operation, thread forms upon a plurality of circular ring sectors with the threads formed on each sector correlated to the threads formed on the other sectors whereby the several sectors when suitably secured in a body member form a thread ring gauge, said mechanism including a chuck, a threaded lapping tool extended longitudinally through the chuck and coaxial therewith, means for rotating the lapping tool relative to the chuck, said chuck having channels therein for guiding respective circular ring sectors in definite radial paths while said sectors are in coplanar relation, a follower shoe confined in each channel for radial movement only, each shoe being engageable with a circular ring sector interposed between said shoe and the lapping tool, and means for independently urging each shoe toward the lapping tool.

7. Mechanism according to claim 6 also including, stops extended radially from the chuck in proximity to the lapping tool, said stops being adapted to engage adjacent end surfaces of respective sectors to prevent radial movement of the sectors beyond a predetermined limit.

8. Mechanism for producing by a lapping operation, thread forms upon a plurality of circular ring sectors with the threads formed on each sector correlated to the threads formed on the other sectors whereby the several sectors when suitably secured in a body member form a thread ring gauge, said mechanism including a threaded lapping tool, a support for the circular ring sectors arranged to confine movement of said sectors to a plane substantially normal to an axis about which the lapping tool and the support are relatively rotatable, means for yieldably urging said sectors radially against the lapping tool, and stops extended from the support for limiting movement of said sectors.

9. Mechanism for producing by a lapping operation, thread forms upon a plurality of circular ring sectors with the threads formed on each sector correlated to the threads formed on the other sectors whereby the several sectors when suitably secured in a body member, form a thread ring gauge; said mechanism including a chuck, a threaded lapping tool extended longitudinally through the chuck and coaxial therewith, means for rotating and reciprocating the lapping tool relative to the chuck, said chuck having channels therein radially extended from the coincident axes of the lapping tool and chuck, a follower shoe confined in each channel for radial movement only, each shoe being engageable with a circular ring sector interposed between said

shoe and the lapping tool, a plate secured to the chuck and overlying the channels, and means within each channel for urging the shoe therein toward the lapping tool.
